Primary Examiner — Karen S Acker*Assistant Examiner* — Wendy Arminio(74) *Attorney, Agent, or Firm* — Jackson IPG PLLC;
Demian K. Jackson(57) **CLAIM**

The ornamental design for a box insert, as shown and described.

DESCRIPTION

FIG. 1 is a perspective view of a box insert showing our new design;

FIG. 2 is a front elevational view thereof;

FIG. 3 is a top plan view thereof;

FIG. 4 is a right side elevational view thereof;

FIG. 5 is a left side elevational view thereof;

FIG. 6 is a rear elevational view thereof; and,

FIG. 7 is a bottom plan view thereof.

The broken lines shown in the drawings depict environmental subject matter only and form no part of the claimed design.
